No. 15,069

June 17, 1884

UNITED STATES PATENT OFFICE.

PAUL GROEBER, OF NEW YORK, N. Y.

DESIGN FOR WALL-PAPER.

SPECIFICATION forming part of Design No. 15,069, dated June 17, 1884.

Application filed April 11, 1884. Term of patent 33 years.

To all whom it may concern:

Be it known that I, PAUL GROEBER, a citizen of the United States, residing in the city of New York, county and State of New York, 5 have invented and produced a new and original Design for a Wall or Ceiling Covering, which is especially intended as a wall-hanging, of which the following is a specification.

The drawing represents a front plan view of 10 the design.

This design consists of the fruit and foliage of the date-palm. The subject is treated to present the appearance of a continuous inter-

mingling of branches and leaves extending in all directions. The fruit is shown in clusters, 15 some in a pendent position, others extending horizontally across the field of the design. The leaves are of lanceolate form, and have the mid-rib clearly defined.

I claim—

The design for a wall-hanging, as herein shown and described.

PAUL GROEBER.
